LIGHT VALVE

John Scott Donal, Jr., East Orange, N. J., assignor to Radio Corporation of America, a corporation of Delaware

Application February 17, 1939, Serial No. 256,833

8 Claims. (Cl. 178—7.5)

My invention relates to television receiving tubes and systems and particularly to tubes of the cathode ray light valve type and method of operation.

In the art of television certain types of light valves utilizing the electron beam of a cathode ray tube to control the illumination of the picture by a valve action on light from an auxiliary light source have been proposed, but have not been altogether feasible because of the inability of the structure to utilize the control action of the beam to the fullest advantage, so that the effect of the electron beam in controlling the light from the auxiliary source has been inadequate. Other difficulties have been encountered because the structure scanned by the electron beam and responding thereto would not rapidly return to a condition of equilibrium to a condition to be rescanned.

The principal object of my invention is to provide a device of the cathode ray light valve type herein the response is adequate to satisfy operating conditions in modern television transmitting and receiving systems. It is also an object to provide a device which is responsive to the control action of a cathode ray beam to a greater degree than heretofore. It is a further object to provide an improved television receiving tube and a method of operation for such tubes where the above difficulties with the prior art devices are overcome. It is a still further object to provide a tube which may be easily fabricated with respect to sealing of the envelope which is mechanically strong, although portions thereof are of very thin material.

In accordance with my invention a local source of substantially constant intensity is developed at a television receiving station and the light is utilized to illuminate a screen or target which is scanned by an electron beam to produce electrostatic charges which control the transparency or opacity of a light transmitting or absorbing medium between the target and the screen upon which an image is to be developed. Further in accordance with my invention I provide a method of operation of a device of the type described wherein an electron beam serves simultaneously to control the illumination from the auxiliary light source and to re-establish conditions of operation suitable for the continuation of the operation steps. These and still other obvious features and advantages of my invention become apparent and will at once suggest themselves to those skilled in the art from the following description taken in connection with the accompanying drawings in which:

Figure 1 is a diagrammatic view of a cathode ray light valve or tube embodying my invention;

Figure 2 is a cross-sectional view of a portion of the envelope structure of the tube shown in Figure 1;

Figure 3 is a curve indicating the secondary electron emission characteristics of certain of the electrode structure shown in Figure 1;

Figure 4 is a schematic representation of certain of the tube structure shown in Figure 1 to illustrate certain aspects of the operation of my device;

Figure 5 is a curve showing secondary electron velocity distribution during the operation of the device shown in Figure 1;

Figure 6 is a partial view of a modified structure incorporating my invention; and,

Figure 7 is a view of a modified target electrode which may be used in my invention.

Referring to Figure 1 which illustrates one embodiment of my invention the cathode ray tube or light valve includes a highly evacuated envelope or bulb 1 of cylindrical shape with a tubular arm or neck section enclosing a conventional electron gun. The cylindrical portion of the bulb 1 is provided at one end thereof with a window 2 of optically uniform material such as glass so that light from a substantially constant intensity light source 3 may be formed into parallel rays of light by the lens system 4 and projected through the cylindrical portion of the bulb 1. The opposite end of the cylindrical portion of the tube is provided with a closure, likewise of optically transparent material which will hereinafter be referred to as the target 5 being positioned so as to be scanned by an electron beam originating from the gun structure in the neck of the bulb 1.

The electron gun assembly is of the conventional type and comprises a cathode 6 from which an electron stream may be drawn, a control electrode 7, and a first anode 8 maintained positive with respect to the cathode 6. The electron stream leaving the first anode 8 is accelerated and concentrated into an electron scanning beam focused on the surface of the target 5 facing the electron gun by a second anode 9 which is preferably a conductive coating on the inner surface of the envelope 1 over a portion of the neck section and also over the inner surface of the cylindrical section with the exception of the window 2 and the target 5. The first anode 8 and the second anode 9 are maintained at the desired positive potentials with respect to the cathode 6

by a potential source such as the battery 10. The control electrode 7 is maintained slightly negative with respect to the cathode 6 by the biasing battery 11 connected between the control electrode and the cathode in series with a source of control potential or video receiver 12 such as used in conventional television receiving systems. Adjacent the end of the first anode 8 furthest removed from the control electrode 7 I provide means for sweeping the electron beam over the target 5. For this purpose I have shown the deflection coils H and V for deflecting the electron beam in mutually perpendicular directions such as in a horizontal and a vertical direction respectively. The coils are supplied with the proper currents for sweeping the beam over the target 5 by conventional horizontal and vertical sweep oscillators, that supplying the coils H being suitably controlled for keystone compensation as well known in the art since the plane of the target 5 is at an angle with respect to the longitudinal axis of the electron gun. It is understood that conventional deflection plates may be substituted for either one or both of the deflection coils if desired.

In accordance with my invention the target 5 is composed of high electrical resistance material having the desired quality of being optically transparent and sealed to the bulb 1 by the use of an intermediate vitreous material 1a as best shown in Figure 2. I have found it necessary to provide a physically rugged target of material having the desired characteristics but which is nevertheless sufficiently thin to meet the operating requirements of my device. In the preferred modifications of my device I prefer mica as a target material because even when sufficiently thin, such as a few thousandths of an inch, it is sufficiently strong to withstand normal atmospheric pressures. The vitreous material 1a is preferably of powdered glass having a coefficient of expansion similar to that of the bulb 1 and target 5. Thus if the bulb 1 is of soft glass such as lead glass the material 1a is preferably of finely divided powdered lead glass having a melting point considerably lower than that of the glass of the bulb 1 and such that it is reasonably fluid at moderate temperatures such as 600° C., and having a coefficient of linear expansion of about 87×10^{-7} ° C. Thus the coefficient of expansion of the glass envelope and the mica are effectively matched by the intermediate glass. I prefer to form a paste of the low melting point powdered glass with water which is then applied to the edges of the bulb 1 and the target 5. The two parts are then pressed together, placed in an oven and heated to about 600° for several minutes or until the powdered glass is fused whereupon the assembly may be cooled and annealed to reduce strains in the seal. It is preferable to make this seal subsequent to the introduction of electrodes into the cylindrical portion of the envelope as later described. However, this seal should preferably be made prior to the introduction of the electrodes forming the electron gun assembly. In addition to several lead glasses of slightly different composition I have sealed mica to lime glass wherein the vitreous material 1a was also powdered lead glass having a coefficient of expansion of 92×10^{-7} ° C. Powdered glasses of somewhat different melting point and coefficients of expansion may be employed although the melting point should be considerably lower than that of the glass of the envelope to which the

mica is sealed. The method of heating the seal may be any which accomplishes the desired end of fusing the intermediate vitreous material without damaging the other components of the seal. It is necessary only that coefficients of expansion of the component parts of the seal shall be of such magnitude that rupture will not result. I have constructed vacuum seals between a mica disc 2 inches in diameter and a cylindrical glass bulb using mica as thin as 0.005 of an inch. Cathode ray tubes provided with mica faces constructed in the foregoing manner have never failed of operation from causes attributable to the seal in question and have withstood atmospheric pressure indefinitely.

Further in accordance with my invention I provide a container or reservoir 13 positioned exterior to the envelope or bulb 1 and adjacent the target 5, the target 5 preferably forming one wall of the container. In the wall of the reservoir 13 and opposite the target 5 I provide a window 14 of glass or other transparent material axially aligned with the target 5 and also with the window 2 so that light from the light source 3 may be projected through the cylindrical section of the bulb 1 and the reservoir 13 and focused on a distant light intercepting or viewing screen 15 by the lens system 16. The target 5 and window 14 constitute in effect a double wall for the envelope or bulb 1. The distance between the adjacent surfaces of the target 5 and the window 14 is not critical although it should be small. Preferably this distance should be substantially equal to the diameter of the electron beam from the electron gun. I have made satisfactory tubes of this type where this distance was less than one millimeter. On one surface of the reservoir window 14, preferably the outside surface thereof, I provide a substantially transparent electrically conductive electrode 17, preferably an exceedingly thin film of metal, such as gold or platinum, which may be sputtered, condensed from the vapor phase or otherwise applied as well known to those familiar with the art of making thin conductive films. While I have shown the electrode 17 on the outside surface of the window 14, it may be deposited on the opposite or inside surface and still meet the requirements of my device. The electrode 17 is preferably connected to the second anode 9 and the battery 10 through low resistance noninductive path although I have operated valves of the type to be described wherein the electrode 17 was isolated from other parts of the device. Within the reservoir I provide a suspending medium or liquid 18 carrying in suspension a great number of light intercepting or absorbing particles 19, which may be oriented to vary the light transmitting characteristics of the device. The characteristics a 00 functions of the liquid 18 and the particles will be considered more fully below. Between the target 5 and the window 14, I provide a mechanical agitator which is maintained in motion during operation of the device.

65 Preferably the agitator may comprise a sheet 20 of mica or other substantially transparent material having an area equivalent to or greater than that of the target 5, which is supported by a mechanical link or rod 21 constrained by gravity to hang vertically as shown in the drawings. The rod 21 passes through a flexible diaphragm 22 so that with the free tip of the rod 21 is moved in a circle the sheet of mica 20 moves so that its edge

remain parallel to themselves and any point on its surface moves in a circular path in the plane of the mica sheet.

Further in accordance with my invention I make the target 5 of such a material that when bombarded by energy such as by a beam of electrons of relatively low velocity the charge produced thereon is negative whereas when bombarded with higher velocity electrons the charge developed thereon is positive in that more secondary electrons are liberated from the target than there are arriving primary electrons, the material also having the property that under still higher velocity electron bombardment fewer secondary electrons are produced than there are arriving electrons. The electron beam produced and focused on the target 5 by the electron gun is modulated in intensity by the control electrode 7. The intensity of the beam over a period of one vertical sweep of the beam may be utilized to produce a picture produced in a manner well known in the art but instead of the picture being rendered visible by the cooperation of a fluorescent material deposited on the target the electrons produce an electrostatic image of the picture, which electrostatic image varies in intensity of charge from area to area in accordance with the light and shade areas from which the signals applied to the control electrode were derived. The electrostatic image on the target 5 orients the particles 19 in the suspension in a manner to be described and thus permits varying amounts of light from the source 3 to pass through the suspension and be focused upon the viewing screen 15, the energy of the viewed picture being controlled but not generated by the electron beam.

Further in accordance with my invention the suspending medium or liquid 18 contained in the reservoir 13 may be any liquid having the desired characteristics as regards electrical resistance, transparency, vapor pressure and viscosity. Thus the suspending medium preferably has very high electrical resistance and transparency and low vapor pressure and viscosity. I have found a number of materials suitable for use as the suspending medium, these materials including liquids such as n-amyl-sebacate, ethyl-hexyl-phthalate, ethyl-hexyl-acetate, and tetrabromomethane. I have found that the performance of the light valve is largely dependent upon the nature of the suspended particles employed and I have been able by altering this nature, to effect a great improvement in the change in light transmission produced by the electrostatic image on the target 5 and in the efficiency of the light control mechanism. Thus, I have used particles of graphite of a size larger than colloidal, particles which microscopic examination have shown to consist of relatively large flat plates. I have also utilized commercial aluminum foil having a thickness less than $\frac{1}{2}$ micron, the foil being subdivided into particles that are very thin compared to their other dimensions. The ratio of the areas of the particles normal to the light rays passing through the light valve in the de-oriented and oriented condition should be as large as possible. This ratio may be termed the shape factor of the particle when taken with respect to the interposed particle area in the two conditions. I have found that with particles of my average shape factor the change in light transmission of the suspension with the application of the field and the efficiency with which the light is controlled may be varied in a predict-

able manner by changing the number of particles contained in a unit volume of the suspending medium. Thus, for television purposes, for example, maximum contrast of the optical image projected as a picture on the viewing screen 15 can be adjusted to the desired value when the light valve is constructed and the average brightness of the picture can be adjusted at any time by changing the intensity of the light source 3. 10 As indicated above, I have found that a suspending medium having low viscosity is desirable so that the suspended particles may readily orient themselves and may likewise be de-oriented, such as by methods later to be described. Therefore 15 with the suspending media having relatively high viscosity I have found it advantageous to heat the liquid to reduce its viscosity, such as by passing current through the coil 23 which is immersed in the liquid. Since the allowable viscosity of the suspending medium is determined by the electrostatic field strength existing between the electrostatic image produced on the target under scansion and the electrode 17, it is impractical to designate an upper viscosity limit. However, I prefer to use a suspending medium having the lowest viscosity compatible with the other desired characteristics such as high resistance and high transmission and low vapor pressure.

Referring to Figure 3 the curve represents the emission of secondary electrons from the scanned surface of the target 5 as ordinates for values of the second anode potential as abscissas. Line A represents unity secondary electron emission, a condition which exists when the secondary electron emission from the target is equivalent in quantity to the number of primary electrons impinging on the target. It will be observed that at second anode potentials below the point marked B on the curve the ratio of secondary electrons to primary electrons is less than unity, whereas for second anode potentials between the points B and C on the curve the secondary emission is greater than unity and for higher potentials than that represented by point C this ratio is again less than unity. It may, therefore, be observed that the curve crosses the line A at two points B and C. The points B and C will therefore be referred to as first and second cross-over respectively. In practicing my method of operation I utilize a target material having a secondary electron emission characteristic of the general configuration to that shown in Figure 3 and operate the tube with a second anode potential exceeding the potential of the second cross-over C. This second cross-over is that potential assumed by an insulated surface when bombarded by an electron beam of such high velocity that for this and all higher velocities of the beam the surface has a secondary emission ratio of less than unity and hence is capable of collecting electrons. I shall, therefore, refer to such a high velocity beam as one which has a volt velocity, that is, velocity in electron volts, greater than the second cross-over of the surface scanned. My mode of operation implies that an electrostatic field of controllable magnitude or time of existence or both is applied to the suspending medium in the reservoir 13 at the point where the electron scanning beam strikes or bombards the surface of the target in order to orient the suspended particles in a manner essentially duplicating the light and shades of the original picture. In accordance with this principle I accomplish my improved operation by scanning the target 5 with an electron beam of 70 volt velocity above the second cross-over of the

material composing the target 5. I have shown in Figure 3 representative values of volt velocity for purposes of explanation but these values are merely illustrative and are not to be interpreted in a limiting sense. Thus, I have shown the first cross-over B as being at approximately 100 volts, the second cross-over C being at 3000 volts which values are representative of certain materials from which the target 5 may be fabricated such as mica, lime glass, and glasses known in the trade as Pyrex and Nonex. This is equivalent to saying that if the target 5 is bombarded by electrons having a volt velocity above 3000, such as 5000, the potential of the target under scansion will be 3000 volts. Thus a net potential difference of 2000 volts for the representative values given is produced between the point of the target which is scanned and the electrode 11. It is this potential difference which serves to orient the particles in the suspending medium. For ease of explanation I have previously referred to the formation of an electrostatic image being formed on the target 5 by the variable intensity electron beam. While this image could be measured and its presence actually determined there are other steps involved in the operation which progressively neutralize the electrostatic image. It is desirable to maintain the electrostatic image for a period just short of the time of scanning the target once in the vertical direction so that the particles in the suspending medium are maintained in an oriented condition thereby giving a longer period of illumination on the viewing screen. However, the electrostatic image should be dissipated within a definite time period, that is the charge on the target 5 should be returned to a datum value prior to the next scanning. It is, therefore, necessary to discharge the electrostatic image and by discharge I mean raising the potential of the scanned areas from the second cross-over potential to a potential approaching that of the second anode, thus in the example given, from 3000 to 5000 volts.

It should be emphasized that the suspension should be kept at its desired orientation for as long as possible consistent with its readiness to be re-actuated by the next scan, for it is precisely by this persistence effect that the valve offers a considerable improvement over mechanical scanning by a factor equal to the number of picture elements. Thus while the discharge and de-orienting mechanisms should not be so slow as to cause undue highlight persistence, neither should they be so fast as to prevent orientation of the particles in the suspension, or so fast as to darken a scanned element before it is necessary.

I have found that when using volt velocities of the beam below second cross-over that is, a secondary emission ratio greater than one at a given volt velocity of the beam, not only is the surface being scanned charged up to second anode potential by the scanning beam but secondary electrons liberated from the target at the scanned points tend to charge the scanned points as well as the adjacent areas toward collector potential, resulting in a detrimental spreading of the charge desired at any point. In my present method of operation, however, when the volt velocity of the beam is above second cross-over for the surface being scanned, adjacent areas while held at a potential approaching that of the second anode are not at the same potential as the scanned areas for the latter are held at the second cross-over potential. Thus if the electrode 11 is held at second anode potential, no effective electrostatic

field exists across the valve at points other than those scanned and I have found spreading of the effect in the valve to be almost completely eliminated.

In a similar manner, when a beam having a lower volt velocity than the second cross-over volt velocity is used to charge a surface up to second anode potential, the maximum potential which may be utilized in aligning the particles in the suspending medium is limited by the potential at which the second cross-over occurs. With my device and method of operation, however, there is no theoretical limitation upon this potential since the potentials of the second anode 9 and of the electrode 11 may be increased as much as desired and the beam will still charge the scanned areas down to 3000 volts, such as for mica.

Furthermore, using a lower volt velocity beam than that represented by the potential of second cross-over, the light valve cannot be actuated by a focused electron beam to produce a fine line of light on the viewing screen 15. This effect is probably due to the action of areas adjacent to the line being scanned being incompletely charged to second anode potential thereby constituting a co-planar grid which prevents adequate escape of secondary electrons from this area. If, however, in accordance with my method an electron beam having a volt velocity above second cross-over is used, the areas under scansion are charged to second cross-over potential thereby eliminating this co-planar grid effect since areas adjacent to those scanned are at a relatively positive potential rather than at a relatively negative potential. I have found therefore that while employing high velocity electrons having a volt velocity above the second cross-over for the particular target material the valve can be actuated to produce valve action for a very small diameter electron beam whereas with lower velocity electrons it cannot be so actuated. Furthermore under this latter condition the collecting field produced by the second anode 9 for collecting secondary electrons from the scanned areas is much improved since the collector is at a considerably higher potential than the surface of the target 5 during scansion.

It is necessary that the response of the light valve be susceptible of continuous modulation or graded response in order to permit the reproduction of half-tones. In the operation of my device, this graded response arises from the fact that over an easily determined range of beam current, depending upon the capacity of the valve, the potential below collector to which an area is charged is a reproducible function of the beam current and hence the light passed by the valve is a function of the beam current. Thus I have found that when the trace of the beam is passed rapidly across the target the brightness of the line obtained may be varied smoothly from zero to a maximum by varying the current in the scanning beam.

During the operation of devices such as shown in Figure 1 I have found that if the electrical resistance of the suspending medium is less than the resistance of the target 5 polarization occurs which may interfere with the desired operation of the device. Thus if the resistance of the suspending medium is too low with respect to the resistance of the target, the electrostatic field across the suspending medium falls to zero too quickly and the condition of orientation of the suspended particles is changed. It may, therefore, be desirable to utilize a target material

having the same resistance as that of the suspending medium. In the present device using mica as a material for the target 5 and one of the liquids mentioned above as the suspending medium, this polarization effect is not serious. However, it will be found advantageous to match the resistance of the target material with that of the suspending medium as closely as possible.

In the operation of the device shown in Figure 1 I provide a step in the operation of discharging the scanned areas which are at or near the potential of the second cross-over back to second anode potential. The necessity of this step may be seen from an examination of Figure 4 which shows a fragmentary cross-section of the light valve elements in Figure 1. Assume that the electrode 17 and the second anode 9 are maintained at 5000 volts with respect to the cathode of the tube and that the second cross-over of the surface of the target 5 is at 3000 volts which is representative of a material such as mica. Referring to Figure 4, the surface of the target 5 scanned by the electron beam is indicated at C, the opposite surface as E, the surface of the window 14 adjacent the suspending medium as F, and the electrode 17 on the opposite surface of the window as G. Potentials of a given area on these four surfaces under various conditions of operation are shown in the following tabulation:

	D	E	F	G
(a) Before scanning	Volts	Volts	Volts	Volts
(b) Immediately after scanning	5,000	5,000	5,000	5,000
(c) After polarization	3,000	3,500	4,500	5,000
(d) After discharge	3,000	4,000	4,000	5,000
(e) After reverse polarization	5,000	6,000	4,000	5,000
	5,000	5,000	5,000	5,000

It is assumed that the structure of Figure 4 is at a potential of 5000 volts before scanning. Immediately after scanning, there is a field across the whole valve and that across the suspending medium causes the suspended particles to be oriented. These two conditions are shown in the above tabulation by (a) and (b). Polarization then takes place and the electrostatic field across the suspension falls to zero as shown by (c). If there is no discharge mechanism, the scanned area remains at 3000 volts and when the beam returns a second time for rescanning of this area it can have no further effect upon the area. Thus, I have found for a representative tube of the type described that for a weak discharging mechanism a line scanned thirty times per second maintains the suspended particles in an oriented condition and maintains the illumination of this line on the viewing screen substantially constant but when the line was scanned about 13,000 times per second the line of light on the viewing screen faded out since in the latter case the scanned area remained at second cross-over indefinitely and, due to polarization, there was no further field available to keep the suspended particles oriented. If however, as in (d) of the above tabulation, the scanned area of the target 5 is discharged back to collector potential the potential of the opposite surface of the target is carried momentarily above that of the surface scanned and the suspension is subjected to a reversed field which tends to reorient the suspended particles or maintain the state of orientation. Finally after a second polarization presented by (e) the field across the device again falls to zero and the given area of the target is ready for another scanning and a repe-

tion of the cycle. It will be appreciated that the above description is followed in its essentials when the transparent electrode 18 is on the suspension side of the window 14 and that the steps (a) to (e) are not necessarily distinct. Thus (d) may be taking place before (c) is applied, and (e) before (d) is applied.

The mechanism of my step of discharge is as follows. During the charging of the area down to the potential of second cross-over, fewer secondary electrons leave the scanned area than there are primary electrons arriving. When the number of secondary electrons is equal to the number of primary electrons the scanned area assumes the potential at which the secondary emission ratio is unity. Referring to Figure 5 which shows the velocity distribution of secondary electrons emitted by the target 5, it may be seen that the majority of the electrons have an initial velocity of only a few volts represented as group K. Let it be assumed that an area has been scanned and left at a potential of 3000 volts and that an adjacent area is then scanned and charged to the same potential. The high velocity groups J and L reach the area to be discharged with relatively high velocity and they tend to charge it to a potential approaching the second anode potential such as 5000 volts since these higher velocity secondary electrons J and L arrive at the latter area with a velocity corresponding to a secondary emission ratio greater than one. Leakage from adjacent areas of the target 5 at higher potential to areas at lower potential aids in raising the potential of the area to be discharged. Since the potential difference between these areas is quite high the leakage is sufficient to materially help the discharge action. After the charged areas have risen in potential by about 100 volts by reason of leakage all of the groups of electrons including group K at low initial velocity are accelerated to the area to be discharged and tend to charge it toward second anode potential.

I have found that it may be advantageous to depend not only on the initial velocity of the secondary electrons liberated from the target under scanion but to provide means for producing a more copious supply of secondary electrons to be used for discharge purposes. Therefore in accordance with one modification of my invention shown in Figure 6 I provide a secondary electron emitting grid-like electrode 24 in a plane parallel to the target 5 and between the second anode 9 and the target. In this type of structure I prefer to operate the second anode at a somewhat lower potential than previously indicated that is below the second cross-over potential of the target 5 such as at 2500 volts and apply the higher potential such as 5000 volts to a third anode 25 which may be a conductive coating on the wall of the tube between the electrode 24 and the target 5. The electrode 24 is operated at a potential between that of the second and third anodes and slightly below second cross-over potential such as 2700 volts. I have found that the electrode 24 when made of a fine wire mesh bright nickel screen having a hole opening 50-60% with respect to total area is satisfactory for good operation. However the hole opening may be increased if materials having higher secondary emission than bright nickel are used. The operation of the tube or light valve shown in Figure 6 is similar to that described in connection with Figure 1 except that the function of the second anode 9 is transferred to the third anode

25. With such an arrangement the secondary electrons liberated from the electrode 24 supplement those liberated from the target 5 so that, considering the curve of Figure 5 as applying to secondary electrons liberated from the electrode 24, the electrons such as the group K, may be accelerated to the recently scanned areas of the target by the field generated by the third anode and reach them with such velocity that additional secondary electrons or tertiary electrons are produced.

It should be noted that my present discharge mechanism prevents the effective repetitive development of potentials which differ from that of the second anode by more than the electron volt velocity corresponding to the second cross-over, for the adjacent areas can only be charged up until electrons from the scanned spot reach them with this velocity, at which point the secondary-emission ratio is reduced to unity. Thus 20 for my device as described, the preferred maximum second anode potential is about 6000 volts, or, in general, twice the potential of the second cross-over of the scanned area. A higher second anode potential would not be harmful but would merely result in a bias across the valve, which could be reduced to zero by reducing the potential of the electrode 17 below that of the second anode. In certain cases it might be advantageous to operate with a second anode potential above (in this case) 6000 volts, for then the surface potential after discharge is reduced below that of the second anode and the collecting field for the tertiary electrons produced by secondaries reaching adjacent areas is thereby increased.

I have found that while the use of the electrode 24 and third anode 25 shown in Figure 6 is advantageous in producing the required number of secondary electrons for effectively discharging the scanned areas of the target, it nevertheless interposes light absorbing or reflecting material between the light source 3 and the viewing screen 15 thereby effectively reducing illumination on the viewing screen and interfering with the ideal operation of the device. Therefore, in accordance with a further teaching of my invention I may generate additional secondary electrons directly in the plane of the target without interposing any light absorbing medium between the light source 3 and the target 5. As shown in Figure 7 I may utilize an electrode structure surrounding and preferably in the plane of the target 5 for the purpose of generating secondary electron emission with which to discharge the target. Referring to Figure 7 which shows only the target 5 and certain associated structure which may be substituted for the target shown in Figure 1, I provide a secondary electron emitting electrode 26 which surrounds the target 5 preferably lying in a plane substantially coplanar therewith. I prefer to form the electrode 26 by depositing a film of metal around the edge or edges of the target 5. The metal may be in suspension and painted thereon to form the electrode 26. This electrode 26 is connected to a somewhat lower potential than that of the second anode 9 so that secondary electrons from the electrode 26 may be accelerated to the target 5. The electrode 26 should be of a material having a high secondary emission ratio at the particular voltage applied thereto and may be made of a metal such as bright nickel or platinum or of an alloy known to have high secondary electron emission characteristics. The metal of which the electrode 75

26 is made, such as bright nickel or platinum, has a considerably higher secondary emission second cross-over than the target 5 so that the number of secondary electrons emitted by this electrode when bombarded by the beam from the electron gun will greatly exceed and supplement the number of secondary electrons emitted by the target proper. While I have disclosed the electrode 26 as being of metal, it may be of any material which has a high secondary emission second cross-over or of material having a second cross-over equivalent to or lower than that of the target proper, it may be operated at a somewhat lower potential than at second anode potential.

During the operation of the device incorporating a target such as shown in Figure 7 the target is scanned by the electron beam from the gun through the action of the coils H and V and is also caused to over-scan the target 5 and impinge on the electrode 26 at the beginning and end of each line sweep. Also in accordance with my invention the intensity of the electron beam may be increased during the time or times it impinges upon the electrode 26 so that even greater quantities of secondary electrons may be emitted. This desired action may be obtained by removing or reducing the bias applied to the control electrode 7 at the beginning and end of each line sweep.

30 From the foregoing it will be evident that I have provided a tube or light valve suitable for television reception and a method of operating such tubes wherein many disadvantages of the prior art are obviated. It will be understood that my improved method of operation is not limited to the specific structure set forth. Thus the electron beam provided for scanning the target may be formed by other structure than the electron gun shown, for example, a beam of high velocity photoelectrons might be utilized. It is likewise obvious that the target may be discharged by means other than those shown in the various modifications of my invention. 35 Therefore, while I have indicated the preferred embodiments of my invention of which I am now aware and have also indicated only one specific application for which my invention may be employed, it will be apparent that my inventor 40 is by no means limited to the exact forms illustrated or the use indicated, but that many variations may be made in the particular structure used and the purpose for which it is employed without departing from the scope of my invention as set forth in the appended claims.

55 What I claim as new is:

1. In a system for television reception a cathode ray tube including a light transmitting double end wall of electrically insulating material having an area at least equal to the summation of elemental picture point areas for which reception is desired, an electron gun within said tube to generate an electron beam of elemental picture area and of variable intensity, a suspension of light intercepting non-magnetic particles in liquid carrier between and coextensive with the said area of said double wall, means to scan the inner surface of one wall of said double wall with said electron beam to produce thereon an electrostatic image over elemental picture areas representative of the intensity of said beam, and means to impress an electrostatic field corresponding in spatial intensity to said electrostatic image across said suspension said means including an electrode adjacent and coextensive with

the picture area of the other wall, the said suspension lying between said one wall and said electrode of said double end wall whereby an electrostatic field may be developed through said suspension and the light transmitting properties of the said suspension may be varied in accordance with the intensity of said beam.

2. In a system for television reception, a cathode ray tube having a light transmitting target of a material which liberates fewer secondary electrons than incident electrons when bombarded with a high velocity cathode ray beam, a container joined to said tube said container having a light transmitting window opposite and axially aligned with said target, a suspension of light absorbing particles in a liquid carrier in said container and between said target and said window, means including an electron gun within said tube to generate an electron beam having such a high velocity that when incident upon said target fewer secondary electrons than incident electrons are generated, whereas a beam of lower velocity generates more secondary electrons, and a beam of still lower velocity generates fewer secondary electrons than the electrons incident on said target, means to vary the intensity of said beam and means to scan said beam over said target to vary the light transmitting properties of said suspension in accordance with the intensity of said beam.

3. In a system for television reception, a cathode ray tube having a mica target, a container joined to said tube said container having a light transmitting window opposite and in alignment with said mica target, a suspension of light absorbing particles in a liquid carrier in said container and between said target and said window, means within said tube to generate an electron beam, means to vary the intensity of said beam, means to accelerate said beam to a volt velocity in excess of 3000 to produce such a high beam velocity that when incident upon said target fewer secondary electrons than incident electrons are generated, whereas a beam of lower velocity generates more secondary electrons, and a beam of still lower velocity generates fewer secondary electrons than the electrons incident on said target, and means to scan said beam over said target to vary the light transmitting properties of said suspension in accordance with the intensity of said beam.

4. In a system for television reception a cathode ray tube having a light transmitting target of a material which liberates fewer secondary electrons than incident electrons when bombarded with a high velocity cathode ray beam, an electron gun for producing a variable intensity electron beam, an anode for accelerating and focusing said beam on said target, means to scan said beam over said target to produce thereon an electrostatic image having a charge from area to area thereof representative of the intensity of said beam, a perforated screen interposed in the path of said beam to produce secondary electrons, an electrode between said perforated screen and said target to accelerate secondary electrons toward said target, means to maintain said anode, said screen, and said electrode at progressively increasing positive potentials with respect to said electron gun, a container adjacent said target the target forming one wall of said container, a light transparent wall in said container opposite and in alignment with said target and a suspension of light absorbing particles in a liquid carrier in said con-

tainer and between said target and said wall, said particles being opaque and of irregular shape and having the property of individually rotating to present a smaller area in a direction perpendicular to said walls to intercept a minimum of light when subjected to an electrostatic field between the target and said wall.

5. Apparatus for television reception comprising a cathode ray light valve device having an evacuated envelope, an electron gun in said envelope for developing an electron beam of elemental cross-section picture area and of variable intensity, an electrically insulating target of extended picture area forming one wall of said envelope, a light transparent window exposed to and in axial alignment with said target, an electrode adapted to liberate secondary electrons adjacent said target and exposed to said electron gun, means to scan said beam over said target to generate an electrostatic image on said target representative of the intensity of said electron beam and over said electrode to develop secondary electrons, a container joined to said envelope having the said target as one wall thereof, a window in said container forming another wall thereof opposite said target and in axial alignment with said first mentioned window, a suspension of light intercepting particles in a liquid carrier filling the space between the walls of said container and an electrode adjacent the said other wall to subject the particles in said liquid carrier to the said electrostatic image to thereby vary the light transmitting properties of the said suspension in accordance with the intensity of said beam.

6. Apparatus for television reception comprising a cathode ray light valve device having a light transmitting target forming one wall of an envelope, a container adjacent said target, a light transmitting element forming a closure for said container opposite to and in alignment with said target, a light transmitting electrode over one surface of said light transmitting element opposite the target, a suspension of light intercepting particles in a liquid carrier in said container, means to generate an electron beam, means to vary the intensity of said beam, means to scan the surface of said target opposite that in contact with said suspension with the variable intensity beam of electrons to produce an electrostatic field between said target and said electrode for aligning the light absorbing particles in the suspension, and substantially transparent means wholly interposed between the target and light transmitting element for maintaining the suspension in agitation.

7. Means for receiving television signals comprising a tube having a double end wall, a suspension of light intercepting particles in a liquid carrier between the said double end wall, electronic means to vary the light transmitting properties of said suspension in accordance with the received television signal, means immersed in said liquid carrier and wholly interposed between the walls of said double end wall for maintaining the suspension in agitation and means for varying the viscosity of said liquid carrier during operation of the tube.

8. Means for television reception comprising a cathode ray tube having an envelope, a mica target sealed to said envelope and forming one wall thereof, a light transmitting window in alignment with said mica target and forming another wall of said envelope, a container adjacent said envelope having a light transparent wall oppo-

site said target and in axial alignment with said target and said other wall of said envelope, a suspension of light absorbing material in a liquid carrier in said container, means wholly interposed between said target and the wall of said container for maintaining said suspension in agitation, said means comprising a sheet of sub-

stantially transparent material, means to move said mentioned means in a plane parallel to the plane of the target and means within the envelope to scan said target with a variable intensity high velocity electron beam.

JOHN SCOTT DONAL, JR.
